WATCHCASE

Samuel Kramer and Julius Kahn, New York,
N. Y., assignors to Pioneer Watch Case Co. Inc.,
Mount Vernon, N. Y., a corporation of New York

Application June 17, 1941, Serial No. 398,366

2 Claims.

(CL 58—98)

This invention relates generally to watchcases and more particularly to watchcases of the watertight type, that is, watchcases constructed so as to prevent the entrance of foreign matter and particularly of moisture, into its interior.

The general object of our invention is the provision in a watchcase of a construction that is simple, inexpensive and effective for excluding moisture and other foreign matter from the interior of the watchcase.

Among the more particular objects of our invention are: the provision of a watertight joint between the watch crystal and the part or parts upon which it seats and the provision of an arrangement of two members between which the perimeter of the crystal is clamped to provide a watertight joint, one of said members being adjustable relatively to the other to effect the clamping operation.

A still further group of objects of our invention includes the provision in a watchcase of a watertight joint for securing the watchcase back in position; the provision of a watertight joint between the watchcase back and a watchcase member, said joint being effected by the engagement between an external upwardly extending flange on the back and a downwardly opening slot intermediate the thickness of the other member.

A still further group of objects resides in the provision of a single member which forms at one end a watertight joint with the crystal and at the other end a watertight joint with the back, said joints being so arranged and constructed as to be adjustable independently of each other and more particularly an assembly of a watch crystal, a watch back and a member to provide a watertight casing.

Among the objects of our invention are: the provision of an arrangement for attaining a watertight joint between the crystal and the bezel comprising a threaded bore in the bezel and a flange thereon to receive the rim of the crystal and a member in threaded engagement with the threaded bore of the bezel for pressing the crystal to its seat; the provision of a joint between the back and the member comprising a threaded bore in the member, a threaded engagement of the back with said bore and a flange in one member fitting into a groove in the other member.

Among the more particular objects of our invention is further the provision of a simple construction in a watertight watchcase, whereby a watertight joint is provided at the front or crystal side of the watch, and a second watertight joint is provided between the back and the watch, and whereby the tightening of these joints may be effected entirely independently of each other.

A further particular object of our invention is the provision in a watchcase of a watertight

joint having the parts thereof pressed together by means distributed along substantially the entire extent of the joint.

In the drawing we have shown an illustrative embodiment of the watchcase in accordance with our invention in which these objects are attained in a specific construction wherein the casing comprises a crystal, a bezel, and a back, the bezel being threaded internally to receive at one end thereof a threaded member which engages the crystal against one end of the bezel to form a watertight joint at that end, and to receive at the other end an externally threaded flange projecting upwardly from the back member with the flange engaged in a slot in the bottom of the bezel to form a watertight joint at the other end.

In the drawing:

Figure 1 is a top plan view of a watch the case of which is representative of one illustrative embodiment of our invention;

Figure 2 is a bottom plan view of the same;

Figure 3 is a sectional view taken substantially on the plane indicated by the line 3—3 of Figure 1, looking in the direction of the arrows, of the case of the watch shown in said figure;

Figure 4 is an exploded view showing fragments of the various portions of the case of the watch of Figure 1 grouped approximately as they appear in the completed assembly, but spaced from each other; and

Figure 5 is a perspective view of one of the elements of the case of the watch of Figure 1.

Referring now to the drawing in detail, we have shown at 10 the bezel of our improved watchcase, which bezel is provided at its upper end with an overhanging flange 11, on the inner surface of which is shown seated a compressible washer or gasket 12, on which, in turn, seats the rim or flange 13 of the crystal 14. The gasket 12 may be of any suitable or preferred material for the purpose, such for example, as India rubber. The bezel is headed annularly as shown at 10a for functioning a holder and tool for assembly and disassembly of the parts.

The bezel 10 is shown at 15 as having its inner wall or bore of uniform diameter throughout and is threaded substantially throughout its full length. Threadedly received on this bore at one end is a ring 16 which is threaded on its exterior as indicated at 15a, and which when fully threaded upwardly to its position of Figure 3 serves to hold the crystal 14 in place in its seat on the flange 11 of the bezel 10, for which purpose it is provided with a flat end face 16a.

It will be observed that the forces tending to urge the ring 16 against the rim 12 of the crystal are distributed substantially uniformly throughout the extent of the joint, this being due to the screw threaded mounting of the ring 16, whereby a much more effective joint is provided than where the compressive forces are localized such

as where screws are used, as for example in United States Patent #2,229,979.

The back of the watchcase is shown at 17. It is in general of shallow cup shape, with a bottom 18 and a rim 19, which latter is divided at the top into two concentric annular flanges 20 and 21, separated from each other by an annular groove 22.

The bezel 10 has its lower edge formed with two flanges 23 and 24 separated by an annular groove 25, and these are so dimensioned and disposed relatively to the flanges and groove of the back, that the flange 21 of the latter will enter the groove 25 of the former, when the bezel and the back are brought into assembled relation.

A gasket or washer 26 of any suitable or preferred compressible material is shown positioned within the groove 25. Means for causing the flange 21 to compress the washer 26 in the groove 25, and thereby to effect a watertight closure, are provided. Such means may be a male screw thread 21 on the outside of flange 20 in engagement with threads 15 on the inside of the bezel. Obviously the gasket 26 will best serve its purpose when its dimensions are such that it will fill the space in groove 25.

Again it will be observed that the compressive forces for tightening the joint are distributed substantially uniformly throughout its extent.

The bezel 10 is shown provided with a bushing or stem 28 at one side thereof within the bore 29 of which the stud (not shown) of the crown 30 is adapted to seat.

A watertight joint is also preferably provided between this stud and the bore 29. This joint may be of the type shown in the aforementioned United States Patent #2,229,979.

In order to permit of a connection between the crown and the stem of the movement, the ring 16 may have a portion cut away, as at 31, at the point thereof which registers with the opening 29 when the ring is in place.

The ring 16 is further shown provided with notches 32 which are adapted to be engaged by a tool, whereby adjustment of the ring 16 is readily effected.

By referring to Figure 2 it will be observed that we have shown the back 17 as provided with facets 33 on its periphery. These are convenient for effecting adjustment of the back, without danger of injury to the finish of the back.

It will now be observed that adjustment of the joint between the bezel and the crystal may be effected entirely independently of the joint between the back and the bezel, which has the obvious advantage that each may be properly adjusted to its maximum effectiveness.

It will further be observed that by the use of our simple and inexpensive construction watchcases may be made completely watertight.

While we have herein disclosed one illustrative embodiment of our invention, it will be understood that our invention may be embodied in many other forms without departing from the spirit thereof, as will be obvious to those skilled in the art. It is also to be understood that the disclosure herein is by way of illustration merely and is not to be interpreted in a limiting sense, and that we do not limit ourselves other than as called for by the prior art.

Having thus described our invention and illustrated its use, what we claim as new and desire to secure by Letters Patent, is:

1. A watchcase comprising an annular body member and a bottom closure therefor, said body

member having its bore threaded and of uniform diameter throughout its length and a bezel retaining flange extending inwardly from its upper end and an annular groove extending upwardly from its bottom surface to define two spaced apart downwardly directed annular flanges the bore of the inner flange being comprised of the lower end of the aforementioned screw threaded bore; said bottom closure member being comprised of a bottom and an annular peripheral wall extending upwardly from said bottom, said upwardly extending peripheral wall having an annular space extending downwardly from its upper surface to define two spaced apart upwardly directed concentric annular flanges, the outer surface of the inner annular flange being threaded and of the same diameter as the threaded bore of the body member and the thickness of the outer annular flange being approximately equal to the width of the said annular groove extending upwardly from the bottom of the body member; whereby the inner upwardly extending flange of the bottom closure member can have its outer wall threaded on the lower portion of the inner threaded bore of the body member to cause the outer upwardly extending flange of said bottom closure member to engage in the annular groove extending upwardly from the bottom surface of the body member to engage a washer received in said angular space and form a watertight joint.

2. A watchcase comprising an annular body member, a locking ring and a bottom closure therefor, said body member having its bore threaded and of uniform diameter throughout its length and a bezel retaining flange extending inwardly from its upper end and an annular groove extending upwardly from its bottom surface to define two spaced apart downwardly directed annular flanges the bore of the inner flange being comprised of the lower end of the aforementioned screw threaded bore; said bottom closure member being comprised of a bottom and an annular peripheral wall extending upwardly from said bottom, said upwardly extending peripheral wall having an annular space extending downwardly from its upper surface to define two spaced apart upwardly directed concentric annular flanges, the outer surface of the inner annular flange being threaded and of the same diameter as the threaded bore of the body member and the thickness of the outer annular flange being approximately equal to the width of the said annular groove extending upwardly from the bottom of the body member, said locking ring having a threaded outer diameter equal to that of the inner threaded bore of the body member and being of less height than the length of that bore whereby the locking ring can be first threaded upwardly therealong until it engages the bezel and secures it in position against the aforementioned inwardly extending flange of the body member and thereafter the inwardly upwardly extending flange of the bottom closure member can have its outer wall threaded along the lower portion of the threaded bore of the bottom member, to cause the outer upwardly extending flange of said bottom closure member to engage in the annular groove extending upwardly from the bottom surface of the body member to engage a washer received in said angular space and form a watertight joint.

SAMUEL KRAMER.
JULIUS KAHN.
